UNITED STATES PATENT OFFICE.

KNUT TROSDAHL, OF CHRISTIANIA, NORWAY.

ELECTRIC-CURRENT INTERRUPTER.

1,231,221.

Specification of Letters Patent. Patented June 26, 1917.

Application filed May 9, 1917. Serial No. 167,438.

To all whom it may concern:

Be it known that I, KNUT TROSDAHL, a subject of the King of Norway, residing at Christiania, in the Kingdom of Norway, have invented certain new and useful Improvements in Electric-Current Interrupters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention has for its object an electric current limiter of the periodical interruption type, in which the interruption of the electric current is effected by the expansion of a volume of air, heated by means 20 of a resistance, through which the electric current passes. The expansion of the said volume of air acts to press an insulating fluid, such as oil into a channel, containing 25 mercury and forming part of the current circuit. When oil is introduced in the said channel, the string of mercury is divided and the current interrupted.

On the drawing is shown a diagrammatical section through a form of the invention.

The apparatus comprises a vessel 1 of insulating material, such as porcelain, in the interior of which is located a W-shaped channel 2, filled with mercury 3 to such a 35 height that the mercury forms a continual bath through the W-shaped channel.

The side and middle members of the W-shaped channel each open into closed chambers 4, 5 and 6. In the middle chamber 6 40 the surface of the mercury is covered by a layer of oil 7.

The electric current passes from wire 8 through resistance wire 9 in the closed chamber 6 to contact wire 10, dipping into the mercury at the bottom of chamber 4. From here it passes through the mercury in the W-shaped channel and through contact wire 11 in chamber 5 to wire 12 which is connected to lamps or other current consuming apparatus 13.

Parallel to resistance wire 9 is shunted an adjustable resistance 14.

The apparatus acts in the following manner:

55 When the current consumption has reached a certain amount, the current passing

through resistance wire 9 will heat the air in chamber 6 to such an extent that its expansion will press the oil 7 down into the middle members 15, 16 of the W-shaped 60 channel, separating the mercury as indicated in dotted lines on the drawing.

Hereby the current is interrupted, and the air in chamber 6 will be cooled and contract until the strings of mercury in 15 and 16 65 are again reunited, closing the current circuit, whereupon the same operation is repeated until the consumption of current is limited.

The amount of current for which the apparatus will start operating may be regulated by means of shunt resistance 14. 70

In order that the temperature outside the apparatus shall not affect its operation, the sum of the volumes of chambers 4, 5 must 75 be equal to the volume of chamber 6.

Although the layer of oil in the chamber 6 is an advantage in order to minimize the interruption spark and prevent the oxidation of the mercury, it is obvious that the oil may be dispensed with without interfering with the operation of the current interrupter, and this particularly is the case if a non-oxidizing gas, such as nitrogen or the like is used in the chambers. 80

Claims:

1. In an electric current interrupter three closed chambers filled with a gaseous medium, a channel connecting the lower ends of said chambers, a continuous body of mercury, forming part of the current circuit, located in the said connecting channel, and a resistance wire, heated by the electric current, located in the middle chamber, for the purpose of heating the gas in the same 90 and effect interruption of the current by expansion of the said gas, when the current consumption has reached a certain limit. 95

2. In an electric current interrupter three closed chambers filled with a gaseous medium, a channel connecting the lower ends of said chambers, a continuous body of mercury, forming part of the current circuit, located in the said connecting channel, and a resistance wire, heated by the electric 100 current, located in the middle chamber, for the purpose of heating the gas in the same and effect interruption of the current by expansion of the said gas, when the current consumption has reached a certain limit, 105 the volume of said middle chamber being equal to the sum of the volumes of the two 110

other chambers, for the purpose of making the apparatus independent of variations in the outside temperature.

3. In an electric current interrupter three closed chambers filled with a gaseous medium, a channel connecting the lower ends of said chambers, a continuous body of mercury, forming part of the current circuit, located in the said connecting channel, a 10 resistance wire heated by the electric current, located in the middle chamber, for the purpose of heating the gas in the same and effect interruption of the current by ex-

pansion of the said gas, when the current consumption has reached a certain limit, 15 and an adjustable resistance shunted on the circuit in parallel to the heating resistance for the purpose of regulating the apparatus.

In testimony that I claim the foregoing 20 as my invention, I have signed my name in presence of two subscribing witnesses.

KNUT TROSDAHL
